SPACE CONDITION RESPONSIVE INSTRUMENT

Walter I. Bieger, St. Anthony Village, Minn., assignor to Honeywell Inc., Minneapolis, Minn., a corporation of Delaware

Filed June 11, 1965, Ser. No. 85,690

Term of patent 14 years

(Cl. D52—7)

FIG. 1

FIG. 2

FIG. 3

FIGURE 1 is a front view of the space condition responsive instrument embodying my new design;

FIGURE 2 is a side view of my design as seen from the left side of the instrument shown in FIGURE 1; and FIGURE 3 is a cut away side view of my design taken along the line 3—3 of FIGURE 1.

The essential features of my disclosed design reside in the portion shown in full lines in the drawing.

I claim:

The ornamental design for a space condition responsive instrument, substantially as shown and described.
